UNITED STATES PATENT OFFICE.

CHARLES PHILIP MOSHER, OF GROTON, NEW YORK, ASSIGNEE TO CORONA TYPEWRITER CO., INC., A CORPORATION OF NEW YORK.

TYPE-WRITING MACHINE.

1,269,204.

Specification of Letters Patent. Patented June 11, 1918.

Original application filed October 16, 1915, Serial No. 56,242. Divided and this application filed December 24, 1915. Serial No. 68,536.

To all whom it may concern:

Be it known that I, CHARLES PHILIP MOSHER, a citizen of the United States, and a resident of Groton, county of Tompkins, and State of New York, have invented certain new and useful Improvements in Type-Writing Machines, of which the following is a full, clear, and exact description.

This invention relates more particularly to foldable visible or front strike typewriting machines, and is a division of my application Serial No. 56,242, filed October 16, 1915.

One of the principal features of the invention is to provide a mechanism irrespective of the means for operating said mechanism or the parts operated thereby, whereby by a typewriting machine having a universal or standard keyboard and relatively foldable parts may be moved to a folded or unfolded position without any disconnection whatever between the operating means, as the keys, and the means operated by said mechanism.

Another feature of the invention is to provide simple and efficient means whereby type-bars may be made to impart an accelerated movement to a universal bar.

Other features of the invention are to provide a simple and efficient connection between a universal bar and an element operated thereby whereby the connection between the universal bar and said element may be folded; to provide a suspended type-bar actuated universal bar and means whereby mechanism may be operated by said universal bar; to provide means whereby a universal bar may be mounted upon a foldable support and an operative connection maintained between the universal bar and the letter-spacing mechanism for a platen carriage wherein said letter-spacing mechanism is mounted upon a non-folding support; and to provide simple and efficient relatively rotating parts, one part being adapted to be operated by one set of mechanism mounted upon one member of a support and the other part of said mechanism mounted upon another member of said support and adapted to impart movement to other mechanism.

A further feature of the invention is to provide a simple and efficient universal bar

mechanism which may be readily made and assembled.

With these and other objects in view, the invention will be hereinafter more particularly described with reference to the accompanying drawings, which form a part of this application, and will then be pointed out in the claims at the end of the description.

In the drawings, Figure 1 is a longitudinal section, partly in elevation, of one form of foldable typewriting machine embodying my invention.

Fig. 2 is a sectional plan view on a reduced scale, taken on the line II—II of Fig. 1.

Fig. 3 is a transverse section on a still smaller scale, taken on the line III—III of Fig. 1, the type-bars and parts of the key action being removed for better illustration.

Fig. 4 is a vertical section taken on the line IV—IV of Fig. 3; and

Fig. 5 is an enlarged fragmentary section through a part of the mechanism whereby one part of said mechanism may be folded with respect to another without disconnection.

While the invention is shown as applied to a typewriter in which an inclosing case is employed, it will be understood that the invention may be embodied in a machine in which an ordinary or any preferred form of frame may be employed or a frame independent of such case, and that said invention may be employed in typewriters of various constructions.

The casing 10 has a main member 11 and a top member or cover 12 which is hinged at 13 to said main member 11. At the forward lower edge of the main member 11 is a foldable case member 14 which is pivoted or hinged at 15 to said main member 11 so that said member 14 may be folded upwardly and when so folded and the cover 12 thereon moved over and forward, a substantially uniform and regular inclosing case is provided. This member 14 may be held in its open position by means of stays 16 or any other suitable means, and said stays may be slotted as at 17 to engage headed pins or studs 18. The stays are normally forced in one direction by springs 19 and the slots 17

are curved or so arranged that in one position the stays will act as a lock, and when forced against the springs 19 the case member 14 may be moved to its folded position.

5 A foldable support or member 20 is pivotally held to a transversely extending rod or shaft 21 which is rotatably supported in the sides of the main casing member 11. At the forward end of the foldable support 20 the latter is connected by links or legs 22 to the case member 14 so that the support 20 may be folded with the member 14 of the case, the distance between the pivots of the links corresponding to the distance between 10 the hinge 15 and rod 21 to prevent such folding movement, though the lower ends of the links or legs need not necessarily be fastened to the case member 14. The support 20 has sides 23 which may be connected by a transverse bar 24 and mounted in said support 20 is a segment 25. Type-bars 26 are pivoted to the segment in any suitable way, as to a rod 27, and said type-bars are adapted to carry a plurality of type 27^a and are supported at their outer ends on a cushion 28, the latter being held to a cushion supporting frame 29 extending outwardly from and supported by the segment. The type-bars are each normally forced in one direction by 15 springs 30 and are each connected by a link 31 to one arm of a bell-crank lever 32. Each bell-crank lever is pivotally held to a rod or support 33. There are four rods each being adapted to support a plurality of the levers 32. The bell-crank levers 32 each have one arm, as 34, provided with a cam edge 34^a which is adapted to engage a cam edge 35 of key-operated levers 36. These levers 36 have keys 36^a and are supported in groups 20 or banks upon rods or supports 37, which latter are horizontally arranged in the normal operative position of the machine under the rods 33 and correspond in number to said rods 33. As each key is depressed the cam edge 35 will operate its coöperating bell-crank lever and through a link 31 will move the type-bar upwardly and rearward for printing purposes, and by reason of the arrangement in groups or banks a substantially uniform touch is obtained.

50 The platen carriage 38 may have a rear guide or base 39, the upper and lower edges of which are each provided with a groove which is opposed to a groove in transversely extending bars or members 40 and 41 to provide upper and lower raceways for the carriage base or bed, said bars 40 and 41 being secured to a strengthening plate or member 42 held to the rear plate or wall of the main casing member 11. Balls or other anti-friction devices 43 are arranged in the raceways to adapt the bed and carriage to travel easily transversely of the machine. The carriage may have end plates 44 in which is mounted 55 to rotate the usual platen or roll 45. The

carriage may have the usual paper apron 46 and the usual finger knobs 47 for rotating the platen, and may also be provided with line-spacing means, paper fingers and other attachments usually employed in typewriting machines. The parts thus far described may be of any preferred construction.

60 In a foldable typewriting machine it is necessary that provision be made whereby the folding principle involved will permit 70 the operation of certain mechanism by the depression of the keys during the printing operation. As one means, I provide a universal bar 48 which is suspended by arms 49, the latter being pivotally held at 50 to lugs 80 on the type-bar segment 25, there being as many arms 49 or supports as desired for said bar. The universal bar 48 is curved substantially to the curvature of the segment 25 and is adapted to be engaged by the rear cam edge or portion 51 of each of the type-bars 26. The purpose of the cam edge or portion 51 of the type-bars is to start the universal bar gradually during the upward and rearward movement of the type-bars and to 85 give the universal bar an accelerated movement without altering the uniform character of the touch of the keys and in order that no sudden jar on the keys may be apparent to the operator when the type-bars start to 90 actuate said universal bar. At the rear of the universal bar are upwardly extending arms 52. These arms rest idly at their upper ends against the rear surface of the universal bar 48, and at their lower ends are 95 held to a transversely extending rod 53, the latter being pivotally held at its ends in the sides of the support 20. Arms 54 project forwardly from the rod 53 and said arms have their forward ends slotted to engage 100 pins 55 carried by the inner ends of arms 56. The arms 56 are held to the transversely extending pivot rod 21 and serve, when the universal bar moves the arms 52, to rotate the pivot rod 21, the latter being rotatably 105 held at its ends in the side members of the main casing member 11.

110 The rod or shaft 21 has a cam member 57 secured thereto near one end thereof adjacent to the outer surface of one of the sides 115 of the support 20, and this cam member is adapted to engage a slidable coöperating cam member 58. The cam member 57 has one or more substantially V-shaped or otherwise formed portions 59 fitting a correspondingly shaped recess or recesses in the slidable non-rotating cam member 58, the latter being slidably held by a key or otherwise to a fixed sleeve 60 through which one end of the rod 21 passes, said cam member 58 being 120 normally forced inwardly by means of a spring 61. The sliding cam member 58 is provided with an annular groove 61^a which is engaged by the forked end 62 of a lever 63. The lever 63 is substantially bell-crank 125

shaped and is pivoted at 64 to a lug on one of the sides of the main case member 11 and has its upper arm 65 extending inwardly and provided with a slotted or forked end 66 which is adapted to engage a pin 67 extending outward from a rod or element 68, so that on each movement of the lever 63 the said rod 68 by means of the pin 67 will be rocked on its pivot pins or screws located at 10 the ends thereof.

When the keys 36^a are depressed the levers 36 will operate the bell-crank levers 32 and through the links 31 will force the type-bars 26 to carry the type 27^a toward the platen 15 45. As the type-bars are forced upwardly and rearward to a printing position, the cam portion or edge 51 of each type-bar will move the universal bar 48. As the universal bar 48 swings rearward the arms 52 will 20 be also moved and this will raise the arms 54. These arms 54 will through the pins 55 move the arms 56 and partly rotate the pivot rod or shaft 21, and this partial rotation of the shaft or rod 21 will carry the cam member 57 therewith and impart a sliding movement to the cam member 58. Such sliding movement of the cam member 58 will rock the lever 63 on its pivot 64 and this movement of the lever 63 through its engagement with the pin 67 will rock the rod 68. The rod or shaft 21 thus serves as the point of fold for the support 20 and the mechanism operated by the universal bar, and said rod may serve as the direct pivot for the 35 foldable support 20 or may be held to rotate in stationary sleeves which form the direct pivot for said support 20.

The rod 68 or the lever 63 may serve as an element to operate other mechanisms, as for 40 example the ribbon mechanism and escapement mechanism or either of them, or other parts of a typewriting machine, it being the intention of the present invention to claim broadly the universal bar, type-bar action 45 and the means operated by the universal bar to permit relative folding of the parts of a typewriter irrespective of the ultimate mechanism moved by said universal bar. As shown, the rod 68 is adapted to operate 50 an escapement mechanism for the letter-spacing movement of the carriage. The carriage has a rack 69 secured to the base 39, and engaging this rack is a pinion 70, said carriage being attached to a flexible connection 71 which passes about a spring drum 72 tending normally to force the carriage transversely of the machine. The pinion 70 is held to a ratchet wheel 73, and the teeth of this ratchet wheel are engaged by a pawl 74 55 carried by a toothed wheel 75, said pawl permitting the carriage to be moved freely in one direction. The toothed wheel 75 is engaged by the usual loose or limber dog 76 and fixed dog 77, said dogs being held to the 60 rod 68 so that when said rod is operated by

any of the key-operated levers 36 the dogs will be moved to permit the toothed wheel 75 to escape and thereby permit the carriage to move a letter space at each depression of a key 36^a in the usual way. 70

It will be evident that the universal bar in the particular construction shown is foldable with the support 20 and the key action; that one part of the universal bar mechanism is foldable with respect to another 75 part; and that said universal bar is adapted to be given an accelerated movement by each of the type-bars. It will be further evident that the universal bar and the connection between the universal bar and mechanism operated thereby is adapted to be moved by keys forming a part of a standard or universal keyboard, and in the particular construction shown the support 20 and the parts mounted thereon are foldable so as to 80 move the keys toward the platen to make the machine compact and to reduce the cubical contents thereof, and when folded, all the mechanism of the typewriter may be entirely 85 inclosed and protected within the case, 90 though as previously stated the invention is not limited to a writing machine using an inclosing case.

Having thus described my invention, I claim as new and desire to secure by Letters Patent:—

1. In a visible typewriting machine, the combination of a platen carriage, a foldable support movable relatively to said platen carriage, types, key-operated levers forming a part of a universal keyboard and operatively connected to said types to move the same toward the platen and mounted with the types upon said foldable support, a universal bar, and a two-part foldable mechanism operated by the universal bar, a part of said mechanism being mounted on said foldable support and foldable therewith away from the platen carriage. 100

2. In a visible typewriting machine, the combination of supporting means, a platen carriage movable along said supporting means, a foldable support, a universal bar mounted upon said support, key-operated levers forming a part of a universal keyboard mounted upon said foldable support, type-bars one for each key-operated lever also mounted upon said support and adapted to operate the universal bar, and foldable mechanism operatively connected to the universal bar. 115

3. In a visible typewriting machine, the combination of supporting means, a platen carriage movable along said supporting means, mechanism, a shaft operatively connected to move said mechanism, a bell-crank lever having one of its arms engaging a part of said shaft to move the same and having its other arm slotted, a sliding cam member having a grooved portion engaged by said 125 180

- slotted end of the bell-crank lever, a spring normally forcing said member in one direction, a rotary shaft extending transversely of the machine, a cam member held to said shaft and adapted to move the first-mentioned cam member against the tension of the spring to move the bell-crank lever, arms projecting outward from said rotary shaft and provided with pins, a rod, arms having slotted ends held to said rod and engaging said pins, upwardly extending arms held to said rod, a pivotally held universal bar adapted when moved to move said last-mentioned arms and thereby rotate the cam member carrying shaft, and key-operated levers operatively connected to move the universal bar when depressed.
4. In a visible typewriting machine, the combination of a platen carriage, a lever and means operated thereby, two relatively movable cam members, one of which is adapted to move said lever, a universal bar, key-operated levers operatively connected to move the universal bar when depressed, and means operated by the universal bar to rotate one of said cam members.
5. In a visible typewriting machine, the combination of a platen carriage, mechanism coöperating with the platen carriage, a bell-crank lever having one of its arms adapted to move said mechanism and having its other arm slotted, a sliding cam member having a grooved portion engaged by said slotted end of the bell-crank lever, a spring normally forcing said cam member in one direction, a rotary shaft extending transversely of the machine, a second cam member held to said shaft and adapted to move the first-mentioned cam member against the tension of the spring to move the bell-crank lever, arms projecting outwardly from said rotary shaft, a rod, arms held to said rod and operatively connected to the arms of the rotary shaft, upwardly extending arms held to said rod, a pivotally held universal bar adapted when moved to move said arms and thereby rotate the cam member carrying shaft, and key-operated levers operatively connected to move the universal bar.
6. In a typewriting machine, the combination of a platen carriage, mechanism, a movable cam member operatively connected to move said mechanism, a rotary shaft extending transversely of the machine, a cam member held to said shaft and adapted to move the first-mentioned cam member, a universal bar, connections between the universal bar and the shaft to rotate said shaft, and means for operating the universal bar.
7. In a visible typewriting machine, the combination of a platen carriage, a shaft, a bell-crank lever having one of its arms engaging a part of said shaft to move the same and having its other arm slotted, a sliding cam member having a grooved por-
- tion engaged by said slotted end of the bell-crank lever, a spring normally forcing said member in one direction, a rotary shaft extending transversely of the machine, a cam member held to said shaft and adapted to move the first-mentioned cam member against the tension of the spring to move the bell-crank lever, a pivotally held universal bar operatively connected to rotate the cam member carrying shaft, and key-operated levers operatively connected to move the universal bar when depressed.
8. In a visible typewriting machine, the combination of a platen carriage, a rotary shaft extending transversely of the machine, arms projecting outwardly from said rotary shaft and provided with pins, a rod, arms having slotted ends held to said rod and engaging said pins, upwardly extending arms held to said rod, a universal bar adapted when moved to move said last-mentioned arms and thereby rotate said shaft, and key-operated levers operatively connected to move the universal bar when depressed.
9. In a typewriting machine, the combination of a platen carriage, mechanism coöperating with said carriage, foldable key operated levers, a rotary cam member operatively connected with the key operated levers, and a relatively movable coöperating cam member operatively connected to said mechanism, the axis of said rotary cam member being coincident with the point of fold of said key operated levers.
10. In a typewriting machine, the combination of a universal bar, an element operated by said universal bar, key operated levers, type bars operatively connected to the key operated levers and adapted to engage and operate the universal bar, and a foldable operative connection between the universal bar and said element to permit said bar and element to be folded relatively to each other.
11. In a typewriting machine, the combination of a frame, a platen carriage movable in said frame, mechanism supported in the frame and coöperating with the carriage, a foldable support connected with the frame, a universal bar mounted on said support, key-operated levers mounted on the support, type bars mounted on the support and operatively connected to actuate the universal bar, and a foldable and non-separable operating connection between the universal bar and said mechanism.
12. In a typewriting machine, the combination of a frame, an element mounted in the frame adapted to actuate a moving part of a typewriting machine, a foldable support connected with the frame, a universal bar mounted on the support, type bars mounted on the support, key levers mounted on the support and operatively connected to actuate the type bars and universal bar, and

foldable mechanism operatively connecting the universal bar and said element and having its point of fold common with that of said support.

5 13. In a typewriting machine, the combination of a frame, a rock shaft mounted in the frame adapted to actuate a moving part of a typewriting machine, a foldable support connected with the frame, a universal bar mounted on the support, type bars mounted on the support, key levers mounted on the support and operatively connected to actuate the type bars and universal bar, and foldable non-separable mechanism operatively connecting the universal bar and rock shaft.

10 14. In a typewriting machine, the combination of a frame, a foldable support connected with the frame, a universal bar mounted on the support, type bars mounted on the support and operatively connected to impart an accelerated movement to the universal bar, key levers mounted on said support and operatively connected to actuate 25 the type bars, an element supported in the frame adapted to actuate a moving part of the machine, and a foldable operating connection between the universal bar and said element.

20 15. In a typewriting machine, the combination of a frame, a foldable support connected with the frame, a universal bar mounted on the support, type bars mounted on the support and operatively connected to 35 impart an accelerated movement to the universal bar, key levers mounted on said support and operatively connected to actuate the type bars, an element supported in the frame adapted to actuate a moving part of 40 the machine, and foldable non-separable mechanism operatively connecting the universal bar and said element, the point of fold of said mechanism being coincident with the point of fold of said support.

45 16. In a visible typewriting machine, the combination of a two-part support comprising a main member and a front member hinged to the main member to fold upwardly and rearwardly, a platen carriage supported in the main member, key levers mounted on the front member, type bars mounted on said front member and normally held in a substantially horizontal position, a universal bar mounted on the front member, operating connections between the type bars and key levers permitting the type bars and key levers to fold with the front member, an element supported in the main member for actuating a movable part of the machine, and a foldable operating connection between the universal bar and said element.

50 17. In a visible typewriting machine, the combination of a support comprising a main member and a front member hinged to the

main member to fold upwardly and rearwardly, a platen carriage supported in the main member, type bars supported on the front member and having an upward and rearward movement toward the platen carriage, key levers supported on the front member and operatively connected with the type bars, a universal bar mounted on the front member, an element supported on the main member adapted to actuate a moving part of the machine, and operating mechanism connecting the universal bar and said element, said mechanism being foldable and maintaining a constant operative connection between the universal bar and said element. 70 75 80

18. In a visible typewriting machine, the combination of a support comprising a main member and a front member hinged to the main member to fold upwardly and rearwardly, a platen carriage supported in the main member, a universal bar mounted on the front member, type bars mounted on the front member and normally held in a substantially horizontal position, key levers supported on the front member, connections 85 between the key levers and type bars for moving the type bars upwardly and rearwardly toward the platen carriage, connections between the type bars and universal bar for operating the universal bar with an 90 accelerated movement, an element supported on the main member for actuating a moving part of the machine, and foldable operating mechanism connecting the universal bar and said element. 95 100

19. In a typewriting machine, the combination of a frame, mechanism mounted in the frame, a rock shaft mounted in the frame and operatively connected to actuate said mechanism, a foldable support connected with the frame, type bars mounted on the support, key operated levers mounted on the support, a universal bar mounted on the support and operatively connected to be moved when the key operated levers are 110 actuated, and a foldable connection between the universal bar and rock shaft for rocking said shaft. 105

20. In a typewriting machine, the combination of a frame, mechanism mounted in the frame, a rock shaft mounted in the frame and operatively connected to actuate said mechanism, a foldable support connected with the frame, a universal bar mounted on said support, type bars mounted 115 on the support and operatively connected to actuate the universal bar, key-operated levers mounted on the support, and a foldable connection between the universal bar and said rock shaft for rocking the shaft. 120 125

21. In a typewriting machine, the combination of a frame, mechanism mounted in the frame, a rock shaft mounted in the frame and operatively connected to actuate said mechanism, a foldable support con- 130

- 15 nected with the frame, a universal bar mounted on the support, type bars mounted on the support, connections between the type bars and universal bar for operating the universal bar with an accelerated motion, key operated levers mounted on the support, connections between the key operated levers and type bars for actuating the type bars, and a foldable connection between the universal bar and rock shaft for rocking said shaft.
- 20 22. In a typewriting machine, the combination of a frame, mechanism mounted in the frame, a rock shaft mounted in the frame for actuating said mechanism, a lever operatively connected to rock said shaft, a rotatable shaft extending transversely of the machine and supported in the frame, a cam fixed on said rotatable shaft, a coöperating cam slidably and non-rotatably mounted on said shaft and adapted to actuate said lever, a universal bar, key operated levers operatively connected to actuate the universal bar, a support for the universal bar and key operated levers loosely pivoted on the rotatable shaft and adapted to swing about said shaft to enable the support and frame to be folded relatively to each other, and means actuated by the universal bar for operating the rotatable shaft.
- 25 23. In a typewriting machine, the combination of a frame, mechanism supported on the frame, a rotatable shaft journaled in the frame transversely of the machine, key operated levers, a universal bar adapted to be actuated when said key operated levers are operated, a foldable support for the key operated levers and universal bar loosely pivoted on said shaft, means actuated by the universal bar for rotating said shaft, said means maintaining an operative connection at all times.
- 30 24. In a typewriting machine, the combination of a frame, mechanism supported
- 35 in the frame, a rotatable shaft mounted in the frame transversely of the machine, key operated levers, a universal bar adapted to be actuated when said key operated levers are actuated, a foldable support for said key operated levers and universal bar loosely pivoted on said shaft, means actuated by the universal bar for rotating said shaft, and means operated by the rotation of said shaft for actuating said mechanism.
- 40 25. In a typewriting machine, the combination of supporting means comprising two relatively foldable members, mechanism supported on one of said members, a universal bar supported on the other of said members, a rotary pivot shaft forming the point of fold between said members, and a foldable connection between the universal bar and said mechanism for actuating said mechanism, the point of fold of said mechanism being coincident with the axis of said shaft.
- 45 26. In a typewriting machine, the combination of supporting means comprising two relatively foldable members, mechanism supported on one of said members, a universal bar supported on the other of said members, a shaft forming the point of fold between said members, means operated by the universal bar and foldable therewith for rotating said shaft, and means operated by the rotation of said shaft for actuating said mechanism.
- 50 27. In a typewriting machine, the combination of a platen carriage, mechanism co-operating with said carriage, foldable key-operated levers forming a part of a standard keyboard, and two coöperating relatively movable and rotatable cam members, one connected to the key-operated levers to be operated thereby, and the other connected to operate said mechanism, the axis of the cam members being coincident with the line of fold of the key-operated levers.

This specification signed this 21st day of Dec., A. D. 1915.
CHARLES PHILO MOSHER.
